Specification for Design.

Patented July 27, 1915.

Application filed May 3, 1915. Serial No. 25,625. Term of patent 14 years.

To all whom it may concern:

Be it known that I, JOHN ROSS, a citizen of the United States, residing in the city, county, and State of New York, have invented a new, original, and ornamental Design for a Quilted Article, of which the following is a specification, reference being had to the accompanying drawing, forming part thereof.

The figure is a plan view of a portion of

a quilted article showing my new design, the dotted lines representing lines of stitches.

I claim:—

The ornamental design for a quilted article, as shown and described.

JOHN ROSS.
